UNITED STATES PATENT OFFICE.

JULES EUGÈNE MALIVERT, OF PARIS, FRANCE, ASSIGNOR TO THE SOCIETE ANONYME
DES APPAREILS J. E. MALIVERT, OF PARIS, FRANCE.

VAPORIZER FOR LIQUID-FUEL BURNERS.

Application filed December 14, 1921. Serial No. 522,452.

To all whom it may concern:

Be it known that I, JULES EUGÈNE MALIVERT, a citizen of the French Republic, of 9 and 11 Rue du Telegraphe, Paris, France, 5 have invented an Improved Vaporizer for Liquid-Fuel Burners, of which the following is a full, clear, and exact description.

This invention has for its object an improved gasifying device for soldering lamps, 10 soldering-irons, chafing-dishes and other similar articles in which gasoline or petroleum is used. It is adapted to prevent the carbonization of the cotton wick, bringing by capillarity the fuel from the reservoir to 15 the burner, by spacing said wick from the burner and thus insuring the proper functioning of said wick at all times;

To prevent the liquid being drawn from the reservoir in the wick-carrying tube and in 20 the burner, by ensuring the complete conversion of the fuel into gas before it is admitted to the burner.

This apparatus is substantially characterized by a special gasifying sleeve, adapted 25 to produce the complete vaporization of the fuel and a throttle-washer separating this sleeve from the wick and adapted to regulate and limit the admission of the fuel to the gasifying device.

30 In the preferred form of carrying out the invention, the sleeve is made of a sheet of metal which is corrugated and constitutes a kind of tubular bundle.

The washer is perforated with one or 35 more small orifices and is placed flatwise against one end of the sleeve on the side where is admitted the liquid fed by the wick engaged into the reservoir.

The combustible liquid drawn by capillarity in the tubular bundle is divided therein in very small streams or veins so that 40 its perfect vaporization is therefore ensured and preventing any drop of liquid from ever reaching the burner.

45 The invention will be described hereafter, by way of example, in the accompanying drawing in which:

Fig. 1 shows a part, in front view, the essential elements of the improved gasifying device.

50 Fig. 2 is an end view of the same.

Fig. 3 is a front view of the gasifying sleeve.

Fig. 4 is an end view of this sleeve.

55 Fig. 5 illustrates this gasifying device

fitted in a soldering-iron, the latter being partly in section.

As illustrated in the drawing, this gasifying device is constituted by a cylindrical sleeve *a* composed of a kind of tubular bundle arranged about a central channel *a*¹. This channel can remain free and empty, as illustrated or it can be filled by a metal rod so as not to leave any passage of important cross-section. 65

This sleeve *a* is obtained by corrugating a very thin sheet of metal, then by bending it about a mandrel.

On one of the ends of the sleeve is fitted flatwise a washer *b* provided at its center 70 with a small orifice *b*¹ (or more).

When this gasifying device is fitted in a soldering-iron for instance, as shown in Fig. 5, the wick *c* extending from the reservoir *d* and passing in the tube *e* comes 75 against the washer *b* in front of which is placed the sleeve *a* arranged in the bush *f* of the soldering-iron.

In this position, the gasifying device is situated above the ordinary heater *g* and 80 its front end is situated behind the spraying nozzle *h*.

The gasoline contained in the reservoir passes in the wick, passes through the throttle-washer and is distributed in the 85 gasifying sleeve where it is vaporized when it reaches the spraying nozzle.

During its displacement the liquid reaches the gasifying device already in a very divided condition, then, owing to its contact with the sleeve *a* which presents a large surface, it is still better vaporized, either under the action of the heat of the heater *g*, or under the action of the natural heat of the bush *f* when the apparatus is in operation. 95

The forms, details, accessories, materials and dimensions of this gasifying device may of course be varied without departing thereby from the principle of the invention. 100

Claims—

1. An improved gasifying device for soldering lamps, comprising a member having a central passage and longitudinal hollow ribs opening into the central passage, 105 and a throttle-washer at the inlet end of the said member.

2. In a device of the character described, a gasifying sleeve-like member formed of thin corrugated metal and having a disk 110

provided with a small central opening secured to one end thereof.

3. The combination with a soldering iron having a wick-tube and a chamber above the wick-tube, of a corrugated sleeve-like member arranged in the said chamber, and a disk having a small opening and at the lower inlet end of the said member and with which the wick is adapted to engage.
- 10 4. The combination with a lamp comprising a liquid fuel reservoir, a burner, and a

wick interposed therebetween, of a vaporizer interposed between the wick and the burner, and means for restricting the flow of fuel from the wick to the vaporizer, said means comprising an apertured disk-like member between the vaporizer and wick and in engagement with the wick.

The foregoing specification of my Vaporizer for liquid fuel burners signed by me 20 this first day of December, 1921.

JULES EUGÈNE MALIVERT.
